By Langmuir, Parry, Clark & Langmuir Attys.

Patented Mar. 17, 1925.

UNITED STATES PATENT OFFICE.

ARTHUR HUGO MÜLLER, OF BLANKENESE, NEAR HAMBURG, GERMANY.

CANAL LOCK.

Application filed February 18, 1924. Serial No. 693,715.

To all whom it may concern:

Be it known that I, ARTHUR HUGO MÜLLER, citizen of Germany, residing at Blankenese, near Hamburg, Germany, have invented certain new and useful Improvements in a Canal Lock, of which the following is a specification.

The efficiency of a canal-lock depends especially on the rapidity with which the lock chamber can be filled or emptied without endangering the boats or ships by too strong currents or formations of waves. The object of the present invention is to construct a lock, which fully answers these requirements, and also a lock which can be advantageously used, where there is a copious amount of water, for instance in canalized rivers.

The novelty of the present lock consists therein that the living force of the water rushing forth in filling the lock is broken in special appeasing basins, which are arranged at both sides longitudinally to the complete lock, and are separated from the lock chamber proper by a partition wall, which is perforated by a large number of openings similar to a sieve or a grate. By suitably constructing and arranging these basins or side ponds and the channels, which connect them with the upper and lower reach, and which can be closed in any known manner, a perfectly uniform distribution of the water is gained, which enters or leaves the lock chamber at a low speed and thus prevent endangering currents and wave-formations.

The canal-lock described above is well adapted where there is always a copious amount of water. If however, the water is scarce, or at certain times of the year becomes scarce, it is advisable to make some alterations, because the lateral appeasing basins must be completely filled with water each time ships or boats are to be sluiced. By constructing the intermediate floor in these appeasing basins that portion above the floor can be used as a spare basin.

In Fig. 1 of the drawings the plan of a canal-lock is shown, which by way of example is adapted for a canalized river.

Fig. 2 is a section drawn to the line 2—2 of Fig. 1.

Fig. 3 is an elevation of part of the perforated side wall.

Fig. 4 is a modification of the canal-lock adapted to be used as a spare canal-lock, 55 the upper half being shown in plan and the lower half in horizontal section.

Fig. 5 is a section drawn to the line 5—5 of Fig. 4.

In the construction shown in the drawing 60 *a* is the chamber of the lock serving to overcome the water step or body of water produced by the dam or weir *b* in the river *c*. By the movable gates or weirs *d'* and *d''*, which are adapted to be lowered, or by any 65 other means the appeasing basins *e'* and *e''* can be connected with the upper water *c'* and in the same way by gates or weirs *d³* and *d⁴* with the lower water *c²*. The partition walls *f'* and *f''* between the appeasing basins and 70 the chamber are perforated by a large number of openings *g*, the total cross-section of which is in proper proportion to the amount of the sluicing water entering or flowing out in this way that on the one hand the velocity 75 of the water entering the chamber *a* is sufficiently small, to guarantee that no endangering waves or whirl-pools are created, and on the other hand no power is lost to break the waves and the currents by the 80 perforated wall *f*.

To provide for an even or uniform distribution of the current of the passing water to the complete length of the perforated wall and to prevent longitudinal currents in 85 the chamber the gates *d* are arranged as near as possible in the center of the canal-lock, and the appeasing basins are given approximately the shape of a delta the basis of which is a perforated wall, and the apex being formed by the inlet or outlet channels. In order to damp the current of water directly towards the center of the wall the openings are reduced here in number and 90 cross section.

Where the local conditions and the scarcity of water prohibit the arrangement of sufficient large appeasing basins equal or uniform distribution can be gained by the aid of intermediate walls *i* of about half the 100 height of the basin, as may be gathered from the lower half of Fig. 1 and of Fig. 3, cutting up the current labyrinthically.

The reference characters *O*, *W* and *U*, *W* indicate respectively, the high and the low 105 water levels.

In the modification shown in Figs. 4 and 5 the basins are divided by a horizontal intermediate floor k , which is supported by pillars or columns m , the spaces below the floor forming the appeasing basins e^3 and e^4 and the upper spaces forming the spare basins h , which can be brought in connection with the appeasing basins by opening interposed cylindrical valves or gates n .
 10 The spare basins can be moreover connected with the upper and lower water by the gates o and o' , while the appeasing basins e^3 and e^4 can be made to communicate with the upper and lower water by opening the valves
 15 p and p' .

The modified lock shown in Figs. 4 and 5 can be operated in three different ways. Firstly, it can be used in the same manner as is described above with reference to the
 20 Figs. 1-3 that is to say without making use of the spare basins h . Secondly, the lock can be used as a spare lock in which one part of the water is retained in the
 25 spare basins, when the chamber a is emptied. This retained water can later on be used for partly filling the chamber again, thus working on a very economical system. Thirdly, the lock can be used as a combined
 30 spare and quick lock by again retaining part of the water in the spare basins, when emptying the chamber and then slowly filling up the spare basins up to the level of the upper water, so as to enable the lock-chamber to be filled with a large amount
 35 of water from the spare basins, thus working on an economical and at the same time quick operating system. Taking it for granted that the superficial area of the bottom of the spare basins and that of the lock
 40 chamber is equal, one half of the water for filling the chamber a up to the level can be taken from the spare basins, the rest of which is then allowed to slowly run down to the lower water preparatory to the spare
 45 basins again being filled with half the amount of the water contained in the lock-chamber, when this is emptied.

The object of the combined spare and quick lock is to damp the sluicing waves of the upper and lower water. It is true, this is done at the expense of the consumption of water, which in this case is as large as with a common canal-lock, while when operating on the economical system say one third of the amount of water can be spared, taking the area of the spare basins to be equal to that of the lock chamber. The advantage gained in either case consists therein, that with regard to the usual lock constructions time is saved, because by the use of the appeasing basins the force of water is broken and balanced to such an extent, that the filling- and emptying-valve or gate can be dimensioned within such limits as economy and the generation of sluicing

waves in the upper and lower water will warrant. The sluicing waves will be considerably reduced when working on the economical system, and they will be still to a greater extent calmed down in the operation described above as a combined economical and quick operating system.
 70

It will be seen that the canal-lock can be used in a manifold way, depending on the amount of water at hand at the different
 75 times in the year or on other circumstances.

I claim:

1. A canal-lock comprising a lock chamber, an appeasing basin alongside of the lock chamber, a perforated wall intermediate of
 80 the lock chamber and the appeasing basin, inlet- and outlet-gates for the appeasing basin, the inlet-gate adapted to connect the basin with the upper water and the outlet-gate with the lower water.

2. A canal-lock comprising a lock chamber, an appeasing basin alongside of the lock chamber, a perforated wall intermediate of the lock chamber and the appeasing basin, inlet- and outlet-gates for the
 90 appeasing basin, the inlet-gate adapted to connect the basin with the upper water and the outlet-gate with the lower water, the
 95 appeasing basin having in plan somewhat the shape of a delta, and the inlet- and outlet gates being situated near the center of the canal-lock.

3. A canal-lock comprising a lock chamber, an appeasing basin along each side of the lock chamber, perforated walls intermediate of the lock chamber and the
 100 appeasing basins, inlet- and outlet-gates for the appeasing basins, the inlet-gates adapted to connect the basins with the upper water and the outlet-gates with the lower
 105 water.

4. A canal-lock comprising a lock chamber, an appeasing basin, alongside of the lock chamber, a perforated wall intermediate of the lock chamber and the appeasing
 110 basin, inlet- and outlet-gates for the
 115 appeasing basin, the inlet-gate adapted to connect the basin with the upper water and the outlet-gate with the lower water, a spare
 120 basin above the appeasing basin and provided with a valve for connecting with the
 125 appeasing basin.

5. A canal-lock comprising a lock chamber, an appeasing basin, alongside of the lock chamber, a perforated wall intermediate of the lock chamber and the
 130 appeasing basin, inlet- and outlet-gates for the
 135 appeasing basin, the inlet-gate adapted to connect the basin with the upper water and the outlet-gate with the lower water, a spare
 140 basin above the appeasing basin and provided with a valve for connecting with the
 145 appeasing basin, and with valves for connecting with the upper and with the lower
 150 water.

6. A canal-lock comprising a lock-chamber, an appeasing basin along each side of the lock chamber, a perforated wall intermediate of the lock chamber and each appeasing basin, inlet- and outlet-gates for the appeasing basins, the inlet-gates adapted to connect the basins with the upper water

and the outlet-gates with the lower water, a spare basin above each appeasing basin and provided with a valve for connecting with the appeasing basin, and with valves for connecting with the upper and with the lower water. ¹⁰

ARTHUR HUGO MÜLLER.
